DESIGN FOR A KNITTED FABRIC

Herman L. Weisler, Petersburg, Va., assignor to Tubize Chatillon Corporation, a corporation of Delaware

Application June 23, 1937, Serial No. 70,006

Term of patent 7 years

To all whom it may concern:

Be it known that I, Herman L. Weisler, a citizen of the United States and resident of Petersburg, county of Dinwiddie, State of Virginia, have invented a new, original, and ornamental Design for a Knitted Fabric, of which the following is a specification, reference being had to the accompanying drawing, forming part thereof.

The figure is a plan view of the fabric showing my new design.

The figure of the design is the result of purl stitching on a background of plain stitching.

I claim:

The ornamental design for a knitted fabric as shown and described.

HERMAN L. WEISLER.
